(57) CLAIM

I claim the ornamental design for a plush toy, as shown and described herein.

DESCRIPTION

FIG. 1. Is a perspective view of my plush toy design;

FIG. 2. Is a front view thereof;

FIG. 3. Is a rear view thereof;

FIG. 4. Is a left side view thereof;

FIG. 5. Is a right side view thereof;

FIG. 6. is a top view thereof; and,

FIG. 7. Is a bottom view thereof.

The broken lines illustrate portions of a plush toy that form no part of the claimed design.
